Milton S. Salmon, New York, and George Dietz, Jr., Brooklyn, N. Y.

Application June 28, 1944, Serial No. 114,237

Term of patent 14 years

(Cl. D15—1)

To all whom it may concern:

Be it known that we, Milton S. Salmon, a citizen of the United States, and a resident of New York, in the county of Bronx and State of New York, and George Dietz, Jr., a citizen of the United States and a resident of Brooklyn, in the county of Kings and State of New York, have invented a new, original, and ornamental Design for a Chair, of which the following is a specification, reference being had to the accompanying drawing, forming a part thereof.

In the drawing:

We claim:

The ornamental design for a chair, substantially as shown.

MILTON S. SALMON.
GEORGE DIETZ, JR.
